UNITED STATES PATENT OFFICE.

ORSON U. BRADLEY, OF NORTH ADAMS, MASSACHUSETTS.

SPINNING-FRAME ROLL.

1,270,777.

Specification of Letters Patent.

Patented July 2, 1918.

Application filed January 2, 1917. Serial No. 140,156.

To all whom it may concern:

Be it known that I, ORSON U. BRADLEY, a citizen of the United States, residing at North Adams, in the county of Berkshire and State of Massachusetts, have invented 5 certain new and useful Improvements in Spinning-Frame Rolls, of which the following is a specification.

This invention has relation to rolls for 10 spinning frames and has for an object to provide an improved process for covering or facing the same.

Another object of the invention is to 15 provide a covering for spinning rolls of a nature whereby to form a substitute for leather at present employed in covering such rolls.

A still further object of the invention is to 20 provide an improved cover or facing for spinning rolls which will be resilient or yieldable to the extent required by spinning rolls owing to the duty imposed upon the same during operation thereof in the spinning frame.

25 In the accompanying drawings in which similar and corresponding parts are designated by the same characters of reference throughout the several views in which they appear:

30 Figure 1, is a view in side elevation of a conventional type of spinning roll which has been covered according to my process.

Fig. 2, is a sectional view through the roll 35 illustrating the different layers of material and

Fig. 3, is a transverse section through one of the cylindrical portions thereof.

It has heretofore been the practice to cover 40 the cylindrical portions of spinning rolls first with a relatively thick strip of cushioning material such as felt, etc., and subsequently covering said material with a strip of leather, relatively thin and polished upon its exterior. Owing to the expense of 45 leather and disadvantages entering into its use, I propose to obviate this material and substitute other materials applied in a manner peculiar to my process.

50 After the usual manner I apply a strip of cushioning material to the roll said material being indicated at 1 in the drawings. This material may be felt, and is subsequently covered with one or more layers of linen or other fabric impregnated with a composition 55 consisting largely of caoutchouc, one of its derivatives, gutta-percha or other substance

having similar properties. I have found however that the commercial article known commonly as tire tape fulfills the requirements. This impregnated fabric is wound 60 upon the cushioning member, and caused to adhere thereto, and finally one or more layers of paper are gummed to the tape, which tape constitutes a combined filler and binder. In the drawings the filler and binder are indicated at 2, and the exterior layer of paper at 3. Finally a coating of cellulose or its products such as celluloid, is applied to the paper in the form of a solution, and the surface of the paper is covered as well as the 65 edges of the cushioning material and binder.

In a covering constructed in this manner the cushioning member 1 serves its usual purpose and the resiliency thereof is modified by the application of the binder wound 70 thereabout, as by winding the binder more or less tightly around the roll, the cushioning member is compressed. Conversely, by winding the binding tape loosely around the roll the inherent elastic properties of the 75 cushion are permitted to be manifested to its fullest extent. The paper forming the exterior of the roll, especially when impregnated with the solution mentioned above, is given properties which increases coefficient 80 of friction to the desired degree and renders the surface of the material equal for all practical purposes to that provided by leather. Owing to the application of the solution of cellulose or its derivatives, to the 85 edges of the roll covering, the entrance of moisture thereinto is precluded, thereby greatly increasing the durability of the facing.

Moreover, owing to the provision of the binder holding within its structure an 90 adhesive material of the nature set forth, the materials applied exteriorly and interiorly to the binder are held together in a more or less compact form thereby rendering the covering for all practical purposes a single 95 solid thickness. While I do not desire to limit myself to the particular formula of the solution applied to the exterior of the roller, at least not in this application, nevertheless I wish to state that the solution may comprise cellulose, dissolved in ether, benzol, or other suitable solvent, or the solution may comprise a derivative of cellulose, such as celluloid dissolved in a suitable medium.

While I have illustrated and described my 100 invention with some degree of particularity, I realize that various alterations thereover

may be made, particularly with regard to the interposition or interchanging of the elements of my improved facing, or with regard to the chemical substances employed in embodying the facing with a spinning roll. Therefore, I reserve the right and privilege of altering the steps of the process, interchanging the order in which they take place, or otherwise varying the nature of materials employed within the spirit of the invention and the scope of the appended claims.

Having thus described my invention what I claim as new and desire to secure by Letters Patent is:

- 15 1. The herein described process of covering spinning rolls which consists in covering the same with a layer of cushioning material, binding the same with one or more layers of adhesive tape, subsequently applying to the tape one or more layers of paper and finally coating the paper with a solution of cellulose or one of its derivatives.
- 20 2. The herein described process of covering spinning rolls which consists in applying thereto a layer of cushioning material, bind-

ing the same about with a strip of adhesive tape, applying to said tape one or more layers of gummed paper, and finally coating the surface of the paper and the edges of the super-imposed materials with a solution of celluloid.

3. A spinning roll having a facing which comprises an inner layer of cushioning material, a super-imposed layer of adhesive tape wound thereabout, and one or more layers of paper applied to the tape, said paper being finally coated with a solution of cellulose or one of its derivatives.

4. A spinning roll having a facing comprising an inner layer of felt, adhesive tape wound about said felt to compress the same, one or more layers of paper applied to the tape, and a coating of celluloid applied to the paper.

In testimony whereof I affix my signature in presence of two witnesses.

ORSON U. BRADLEY.
